UNITED STATES PATENT OFFICE.

MARIUS PAUL OTTO, OF PARIS, FRANCE.

TUBULAR OZONE-GENERATOR.

1,163,768.

Specification of Letters Patent. Patented Dec. 14, 1915.

Application filed September 18, 1913. Serial No. 790,381.

To all whom it may concern:

Be it known that I, MARIUS PAUL OTTO, a citizen of the Republic of France, residing at Paris, France, have invented certain 5 new and useful Improvements in Tubular Ozone-Generators, of which the following is a specification.

In constructing ozone generators wherein the electrical discharge takes place between 10 two dielectrics, a difficulty is found in cooling the said dielectrics. If the said dielectrics are cooled by means of a current of water, one at least of the circuits must be suitably insulated because it is at high 15 tension. If the electrical discharge takes place between a dielectric and a metal electrode, the latter will always be more or less deeply 20 attacked either by the actual discharges or by the oxidizing substances generated by the discharge.

The present invention has now for its object to provide an improved ozone generator, the novelty of which consists substantially in that one of the two electrodes only is 25 cooled by direct contact with a casing in which a current of cooled water circulates, while the other electrode located at a slight distance from the first electrode is cooled by radiation only.

30 The improved apparatus thus combines from the point of view of water circulation the advantages of an apparatus having a single cooling circulation, and from the point of view of inoxidizability, the advantages of an apparatus having a double dielectric.

Apparatus of this kind may be constructed either with flat dielectrics or with dielectrics formed of concentric tubes.

40 In the latter case the electric discharge takes place in the annular space comprised between two tubes and the air circulates along the generating lines thereof passing either from one end of the tube to the other 45 end, or from both ends of the tube to the middle thereof.

This last construction has considerable advantages namely it does away with the end joints which are so difficult to make, and it 50 realizes with a tubular system, the construction already applied by the present inventor to ozonizers having flat electrodes with central suction.

An embodiment of this invention is illus-

trated by way of example in the accompanying drawings, in which:

Figure 1 is a sectional plan of approximately one half of the improved tubular ozonizer. Fig. 1^a is a similar view of the other half thereof. Fig. 2 is a view half 60 in external elevation and half in sectional elevation of approximately one half of the device. Fig. 2^a is a similar view of the other half thereof. Fig. 3 is a view in half external elevation and half in section taken in 65 a plane at right angles to Fig. 2, the dielectric tubes being omitted from Fig. 3. Fig. 4 is a section on the line C D of Fig. 1. Fig. 5 illustrates the means employed for centering glass tubes. Figs. 6 and 7 are views 70 of details.

As shown, the improved tubular ozonizer is composed substantially of a series of elements similar to the element which is shown in section in Figs. 1 and 1^a. Each element is 75 formed of two tubes of glass or any other dielectric A and B, arranged concentrically and separated from each other by an interval C of a few millimeters. These tubes are centered by a rod d carrying at each of 80 its ends 2 conical supports E¹ E², F¹ F².

The conicity has for its object to insure automatically the centering of the tubes.

The tube A is pierced in its middle portion with a series of holes G¹ G² G³ (Fig. 85 2). These holes open into the suction chamber H. The tube B is lined with a sheet of tin and aluminium. The tube A engages with slight friction in a metal sleeve L of cylindrical shape formed in the body of 90 the apparatus. The current of cooling water circulates around this sleeve. Contact is insured between the tube A and the sleeve L by means of corrugated tin foil or sheets of tinsel suitably arranged.

95 The air or oxygen to be ozonized enters the apparatus through the side chambers I¹ and I², and passes through the annular space comprised between the tubes A and B wherein it is subjected to the action of electrical discharge. It reaches finally the suction chamber H. The walls of this latter chamber are covered with inoxidizable materials K.

100 The drawings illustrate a tubular ozonizer with two elements but it is to be understood that the ozonizers may be constructed with any desired number of elements.

The electric current is supplied to the apparatus by means of a metal rod M, Fig. 2, which is carefully insulated by means of a porcelain sleeve N. A metal part O establishes connection between the elements. The outer tubes are earthed and the inner tubes are at a high potential.

In a case where the circulation of the air takes place longitudinally along the generating lines of the tubes, the central suction chamber H is dispensed with and the air or oxygen to be ozonized passes directly from the chamber I¹ into the chamber I². In such a case the centering cones E¹ E² are made solid and form plugs for stopping up two ends of the electrode B.

It is to be understood that the construction hereinbefore described with two dielectrics and a middle suction chamber without end joints is equally applicable to a tubular ozonizer composed of a dielectric and a metal tube, but in this case the advantage of inoxidizability would be less.

In the types of apparatus hereinbefore described, since the current of cooling water is not in direct contact with the dielectric tubes, there is no risk of the water penetrating into the apparatus if a tube should happen to break for any reason.

Having now described my invention what I claim as new and desire to secure by Letters Patent is:—

1. In ozone apparatus, the combination of a casing having a cooling chamber and

an air-suction chamber therein, electrodes supported in said casing, and a pair of telescoping dielectric tubes embraced by said cooling chamber, the outer tube of said pair having perforations opening into said air-suction chamber.

2. In ozone apparatus, the combination of a casing having an intermediate air-suction chamber and oppositely disposed cooling chambers, electrodes supported in said casing, and a pair of telescoping dielectric tubes extending axially through said casing and embraced by said cooling chamber, the outer tube of said pair having perforations opening into said air-suction chamber.

3. In ozone apparatus, the combination of a casing having an intermediate air-suction chamber and oppositely disposed cooling chambers, electrodes supported in said casing, a pair of telescoping spaced dielectric tubes extending axially through said casing and embraced by said cooling chambers, the outer tube of said pair having perforations opening into said air-suction chamber, and means for centering said tubes within the casing and maintaining the spacing between said tubes.

In testimony whereof I have affixed my signature in presence of two witnesses.

MARIUS PAUL OTTO.
